Primary Examiner — Keli L Hill(74) *Attorney, Agent, or Firm* — Sterne, Kessler, Goldstein & Fox P.L.L.C.(57) **CLAIM**

The ornamental design for an audio speaker system, as shown and described.

DESCRIPTION

FIG. 1 is a perspective view of an audio speaker system in accordance with the present invention;

FIG. 2 is a front view of the embodiment of an audio speaker system depicted in FIG. 1;

FIG. 3 is a rear elevation view of the embodiment of an audio speaker system depicted in FIG. 1;

FIG. 4 is a left side view of the embodiment of an audio speaker system depicted in FIG. 1;

FIG. 5 is a right side view of the embodiment of an audio speaker system depicted in FIG. 1;

FIG. 6 is a top plan view of the embodiment of an audio speaker system depicted in FIG. 1;

FIG. 7 is a bottom view of the embodiment of an audio speaker system depicted in FIG. 1;

FIG. 8 is a top plan view of the embodiment of an audio speaker system depicted in FIG. 1 rotated so that handle is positioned forward; and,

FIG. 9 is a rear elevation view of the embodiment of an audio speaker system depicted in FIG. 1 rotated so that handle is positioned downward.

The broken lines shown are included for the purpose of illustrating portions of the audio speaker system that form no part of the claim.
